GAME BOARD

Ruth M. Boyle, Glendale, Calif.

Application August 31, 1948, Serial No. 148,380

Term of patent 14 years

(Cl. D34—5)

To all whom it may concern:

Be it known that I, Ruth M. Boyle, a citizen of the United States and resident of Glendale, in the State of California, have invented a new, original, and ornamental Design for a Game Board, of which the following is a specification, reference being had to the accompanying drawing, forming part thereof, wherein:

Fig. 1 is a front elevational view of the game board showing my new design;

Fig. 2 is a side elevational view thereof; and

Fig. 3 is a top plan view with the board shown fragmentarily.

The baskets have been omitted from Fig. 1 for convenience of illustration.

I claim:

The ornamental design for a game board, substantially as shown and described.

RUTH M. BOYLE.
